UNITED STATES PATENT OFFICE.

FRANCIS M. BARFIELD, OF SUMMERLAND, MISSISSIPPI.

STUMP-BURNER.

1,112,967.

Specification of Letters Patent.

Patented Oct. 6, 1914.

Application filed April 30, 1912. Serial No. 694,281.

To all whom it may concern:

Be it known that I, FRANCIS M. BARFIELD, a citizen of the United States, residing at Summerland, in the county of Smith and State of Mississippi, have invented new and useful Improvements in Stump-Burners, of which the following is a specification.

This invention relates to furnaces and more particularly to stump burner furnaces, the object of the invention being to provide a simple and efficient device of this character which will be conveniently installed and operated without entailing any great expense.

Further objects of this invention will appear as the following specific description is read in connection with the accompanying drawing, which forms a part of this application, and in which:

Figure 1 is a perspective view of the furnace. Fig. 2 is a sectional view through the same showing the device applied. Fig. 3 shows the blank from which the furnace is formed.

In the specific embodiment of the invention as illustrated herein, the furnace is constructed of a single sheet of metal having the outline of a frustum of a trapezoid and is preferably constructed of a heavy sheet of metal bent upon the lines 1 and 2 to form supporting sides 3 and the inclined top 4. This top is provided with a concave front edge 5 and has a stack aperture in which a smoke stack 6 is adapted to be placed. In applying the device, a hole is dug along the side of a stump so as to get

past the branch roots and so that the furnace may be placed in position to bring the coals against the tap root. After the furnace has been lowered into position and properly filled with coals, the hole is filled in, as shown, and the earth packed around the smoke stack. The coals in the stump will, therefore, smoulder in the manner of charcoal kilns.

What is claimed is:—

A device of the character described comprising a sheet metal blank, said blank having oppositely inclined longitudinal edges and two parallel transverse edges, one of said transverse edges being of a greater length than the other, said blank being formed with two longitudinal parallel lines of fold which are spaced the distance equal to the length of the short transverse edge, whereby a body portion is formed, said body portion being formed along its relatively longer transverse edge with an intermediate recess, said blank being folded upon said lines of fold to form two sides, said sides arranged to set upon their inclined edges to support said body portion, and a tube having its lower end connected to said body portion near said concaved edge.

In testimony whereof I affix my signature in presence of two witnesses.

FRANCIS M. BARFIELD.

Witnesses:

J. B. GRISSOM,
W. H. CALDWELL.
